(57) CLAIM

The ornamental design for a combination of a game board and doll chess pieces, as shown and described.

DESCRIPTION

FIG. 1 is a front, right, and top perspective view of a game board of the combination of a game board and doll chess pieces showing my design.

FIG. 2 is a front view of the game board.

FIG. 3 is a left side view of the game board.

FIG. 4 is a right side view of the game board.

FIG. 5 is a top view of the game board.

FIG. 6 is a bottom view of the game board.

FIG. 7 is a front, left, and bottom perspective view of a doll chess piece of the combination of a board and doll chess pieces showing my design.

FIG. 8 is a rear, left, and bottom perspective view of the doll chess piece.

FIG. 9 is a front view of the doll chess piece.

FIG. 10 is a rear view of the doll chess piece.

FIG. 11 is a left side view of the doll chess piece.

FIG. 12 is a right side view of the doll chess piece.

FIG. 13 is a top view of the doll chess piece.

FIG. 14 is a bottom view of the doll chess piece; and,

FIG. 15 is a perspective view of the combined game board and chess pieces shown in a use state with environment.

The lightened areas within the evenly spaced broken lines regions depict portions of the article that form no part of the claimed design.

The bracket shown in FIG. 15 indicates the collective appearance of the game board and the doll chess pieces; the bracket forms no part of the claimed design.

1 Claim, 15 Drawing Sheets
